UNITED STATES PATENT OFFICE.

FLOYD A. BURKITT, OF DAYTON, OHIO, ASSIGNOR TO THE RECORDING AND COMPUTING MACHINES COMPANY, OF DAYTON, OHIO, A CORPORATION OF OHIO.

FARE-BOX.

1,270,375.

Specification of Letters Patent. Patented June 25, 1918.

Application filed August 11, 1917. Serial No. 185,788.

To all whom it may concern:

Be it known that I, Floyd A. Burkitt, a citizen of the United States, residing at Dayton, in the county of Montgomery and 5 State of Ohio, have invented certain new and useful Improvements in Fare-Boxes, of which the following is a specification, reference being had therein to the accompanying drawing.

10 My invention relates to fare boxes and particularly to coin eliminating mechanism for fare boxes.

The particular object of my invention is to provide a coin eliminating mechanism 15 which will adapt itself to the irregularities of operation and always keep the eliminating finger in yielding engagement with the member upon which the eliminated coin rides to always eliminate the coin.

20 It is an additional object to provide a finger which cannot raise or be interposed in the path of the projections on the coin carrying mechanism resulting in a bent finger and the coin to be eliminated riding 25 under the bent finger.

It has been found to be an advantage to have the eliminating finger or mechanism resiliently pressed against the abutment on which it rides so that in case an odd size 30 coin or counterfeit passes through the fare box the finger will not be moved a portion of the distance it ought to be moved and thereby lie in the path of the coin moving mechanism and become bent. By having the 35 mechanism of my invention it is forced by its normal position and pressed against the abutment so that if an odd size coin does happen to pass into the machine the resilient means will press the finger beyond its 40 normal position in that location and against the abutment out of the path of the means which moves the coin.

In the particular embodiment of my invention herein shown, if the helical spring 45 and the remainder of the mechanism were not constructed and employed as I use them, or their equivalents were not so used, the finger, upon the passage through the machine of an odd size coin, might project in 50 the path of the coin carrying lugs and become bent, thus allowing the coin to pass by into the unlocked box. Mutilated or improper coins would also pass it and the object of the invention be defeated.

55 In the use of these machines it is not de-

sired to return pennies to customers in making change and it is further found that slightly larger coins, such as five cent pieces, are so altered in size by persons operating these machines as to make them equivalent 60 in size to a one cent piece. If a street car conductor, for example, returns such a five cent piece to a customer in change the natural inclination of the customer is to deposit that particular coin in the fare box. 65 If that is done, of course, only one cent is registered on the adding device and therefore the conductor may pocket the other four cents.

To prevent the misoperation just referred 70 to and also to prevent return of any pennies whatever to the customer is the object of this invention. Such coins whether pennies or larger value coins which have been mutilated are deposited in a locked receptacle 75 and cannot be used a second time.

This invention is an improvement upon the copending application of F. B. Kennedy for fare box, filed Aug. 11, 1917, and bearing Serial Number 185,773. 80

In the accompanying drawings, Figure 1 is a side elevation of my fare box and other mechanism which is not the subject of this invention but used in conjunction with it; Fig. 2 is a front elevation of this assembly; 85 Fig. 3 is a front view of the fare box proper with the hopper casing removed and also one of the guide plates removed showing a coin about to be diverted into the locked receptacle. Fig. 4 is a front view of the fare 90 box with the hopper casing removed and the mechanism in its initial position before being operated; Fig. 5 is a rear view of the fare box with the casing removed from a major portion of the mechanism to show the 95 passageway from the eliminating mechanism to the locked receptacle; and Fig. 6 is a detail view of the locked receptacle showing the actuating mechanism for moving the counter. 100

Figs. 1 and 2.—1 is a fare box casing, 2 the operating handle, 3 the locked receptacle, 4 the unlocked receptacle, 5 the counter attached to the locked receptacle, 6 the key hole for the key to unlock the locked receptacle, 7 indicates the supporting means between the fare box and the visual indicator, 8 the counter to indicate the amount of the coin registered, 9 the customary tower into which the fares are deposited, 10 the handle 110

to operate the inspection plate, 11 the visible fare indicating means and 12 the operating handles therefor. 13 are the lugs attached to the fare box casing to enable it to be mounted upon a standard in a street car or other location when being operated.

Figs. 3 and 4.—14 is a coin plate upon which are lugs 15 to pick up the coins indiscriminately. The coin plate turns in the direction of the arrow and picks up a coin from the mass of coins of various denominations indiscriminately mixed at the bottom of the hopper and at the bottom of the coin plate, lifting it until such coin comes in contact with the differential registering arm 16 against its cam surface 17, thus lifting the differential arm a predetermined distance according to the diameter of the coin and therefore its denomination. The coin rides on the finger 18 projected into a groove 19 in the path of the coin having an inclined surface 20 on which the coin travels upwardly against the differential arm and forwardly against its point of exit. 21 indicates openings through which the spring-pressed finger 22 (Fig. 5) projects at requisite intervals to unseat coins which may have stuck on the coin plate at an improper location between the lugs 15 and not in conjunction with the lugs 15.

The coins lift the differential arm varying distances until the star wheel 23 shown in dotted lines is lifted in a manner explained in the patent of F. B. Kennedy, granted Nov. 13, 1917, No. 1,246,608, until the star wheel is brought into line with the proper rack of teeth on the drum 24 which is revolving, being driven from the same source of power as the coin plate 14. This rack of teeth revolves the star wheel 23 pinned to the shaft 26, and consequently revolves the bevel gear 25 which is driven by the same slidable shaft 26. A corresponding spur gear 27 then operates the counter 28 through the miter gear 25.

My invention, however, is directed more particularly to the following, namely, the mechanism for eliminating a certain denomination or denominations of coins. To accomplish this result the coins all actuate the differential arm 16 lifting it a distance proportionate to the size of the coin. When a penny passes through the machine the arm 16 is lifted a sufficient distance to move the cam arm 29 attached at its outer end to a height such that the pin 30 thereon traveling in the cam slot 31 reaches the position of Fig. 3. Here the pin 30 has been rocked by the cam slot 31 so as to actuate the jaws 32 around their pivotal point 33. The pin 30 is carried on these jaws 32 and also carried on the pin 30 is a plate 31^a having a projection 33^a between which and the upper jaw 32 is a spring 34^a. The plate 31^a has fast thereto a spring member 34 and in the

position of Fig. 3 this has been swung through an arc to its operative position which is at that point where the end of the spring rests on the finger 18 and thereby prevents the coin from passing downward to the main receptacle 4. Thus the coin must ride upon the spring 34 and travels across it upwardly behind the plate 35 in Fig. 4 and in front of the coin plate 14. It finally reaches the tube 36 which leads to the locked receptacle 3.

To maintain the differential arm 16 in its raised positions a pawl 37 operates in a ratchet 38 on the end of the arm. A spring 39 tends to pull down the differential arm 16 and this serves to seat the pawl 37 against the ratchet teeth 38. During this period of the operation the registration is effected and then the ratchet is released and the differential arm 16 returned to its normal position. If the deflecting arm 34 has been moved to the position of Fig. 3 by the insertion of a penny in the machine the deflecting arm may then be returned to its normal position by the return of the differential arm 16.

The ratchet releasing mechanism is shown in Fig. 5, an arm 41 being pivoted on a pin 40 which also carries the pawl 37. A finger 42 is attached to the outer end of arm 41 and rides on a cam surface 43 on the rack 24. The cam surface is positioned so that it releases the ratchet and thrusts the arm 42 outwardly between registrations by the teeth on the rack.

In Fig. 5, 36 indicates the eliminator tube leading to the locked eliminator drawer 3, 4 is the main unlocked drawer, 5 is the counter attached to the locked drawer, 2 is the handle which operates the mechanism driving through the gears 46 and 47 both the coin plate and the rack 24. 48 is a spring operating a catch 49 which prevents the unlocked drawer 4 from being pulled out entirely and thus exposing the mechanism to any readjustment of it by the operator.

Fig. 6.—Fig. 6 is an enlarged detail of the mechanism which actuates the counter attached to the locked drawer. Connected with the locked drawer is a shoulder 50 with a slot 51 in it, in which projects a finger 52. This finger 52 is a lever fixed to a shaft 53 connected to the counter. When the drawer is withdrawn this lever is moved a predetermined distance and the counter is thereby actuated. The counter can be of any well known type.

In particular reference to the cam arm 29 and the slot 31, it will be observed that the slot 31 starts with a relatively straight portion and then traces a semicircular path and again straightens out in substantially a straight line. The object of this is to permit the differential arm and the cam arm to

lift certain predetermined distances to register the coins which are to be registered without actuating the eliminating mechanism. When coins of greater size which are to be 5 eliminated lift the differential arm higher than the pin 30 travels into the curved portion of the cam slot 31 and is actuated and deflected so that the finger 34 is placed in the path of the coins.

10 While I have shown and described one embodiment of my invention it will be understood that the same has been chosen for purposes of illustration only, and that I do not desire to be limited to the details of construction shown and described, for obvious modifications will occur to a person skilled in the art.

Having thus fully described my invention, what I claim as new and desire to secure by 20 Letters Patent, is:—

1. In a coin registering mechanism, a hopper comprising an inclined rotatable disk to lift the coins therefrom, a differential operating mechanism, a cam arm depending therefrom, a cam slot therein, a pair of jaws pivoted on the frame, a pin eccentrically located on said jaws and traveling in said slot, resilient means between said jaws, a coin eliminating finger connected at one end 30 to said resilient means and adapted at its other end to be interposed in the path of a coin to deflect said coin, a ratchet on one end of said differential mechanism, a pawl coöperating with said ratchet, means to lock 35 and unlock said differential mechanism and accompanying mechanism, and resilient means to return said mechanism to inoperative position, whereby when said coin has actuated the differential mechanism, said 40 differential mechanism will be locked together with the coin eliminating mechanism to eliminate a coin and after the coin has been eliminated said mechanism will be unlocked and returned to its normal position.

45 2. In a coin registering mechanism, a differential mechanism, a hopper, means for lifting coins to operate the differential mechanism, coöperating means to interpose deflecting means in the path of coins of a 50 predetermined denomination to deflect such coins into a special receptacle, said means including a plate having spaced jaws, and a spring finger having a projection yieldingly held between said spaced jaws, where- 55 by coins of said predetermined denomination will be eliminated.

3. In a coin registering mechanism, a differential mechanism, a hopper, means for lifting coins to operate the differential mechanism, coöperating means to interpose deflecting means in a path of a coin to deflect a coin of predetermined denomination into a predetermined receptacle, means to hold 60 said deflecting means yieldingly in its deflecting position, whereby coins of predeter- 65

mined denomination will be eliminated, and means to lock said differential and eliminating mechanism in position while eliminating a coin and to unlock said mechanism after the coin has been eliminated.

70

4. In a coin registering mechanism, a differential mechanism, a hopper, means for lifting coins to operate the differential mechanism, coöperating means to interpose deflecting means in a path of a coin to deflect 75 a coin of predetermined denomination into a predetermined receptacle, means to hold said deflecting means yieldingly in its deflecting position, whereby coins of predetermined denomination will be eliminated, 80 means to lock said differential and eliminating mechanism in position while eliminating a coin and to unlock said mechanism after the coin has been eliminated, and resilient means to return said mechanism to its normal position.

85

5. In a coin registering mechanism, a hopper comprising an inclined rotatable disk to lift coins therefrom, a differential arm pivoted at one end with a ratchet at the other, 90 a depending cam arm fastened to the outer ratchet end of said differential arm, a cam slot at the outer end of said cam arm, a U-shaped member pivoted beneath said cam arm, a pin eccentrically placed on said U-shaped member and traveling in said slot, a helical spring between the arms of said U-shaped member, a finger attached to said spring at one end adapted to be interposed at the other in the path of a coin to eliminate 95 a coin of predetermined denomination, a pawl coöperating with said ratchet mounted on a shaft, an arm mounted on said shaft, a finger attached to the outer end of said arm and adapted to contact with a cam at 100 its other end, a cam member intermittently brought into contact with the outer end of said finger, resilient means for returning said differential arm and its coöperating mechanism to its normally inoperative position, whereby when said differential arm and coöperating mechanism are moved by 105 a coin to their operative position they are locked in such position and when said coin has been eliminated they are unlocked and 110 returned to their normal position.

115

6. In a coin registering mechanism, a hopper comprising an inclined rotatable disk to lift coins therefrom, a differential arm pivoted at one end with a ratchet at the other, 120 a depending cam arm fastened to the outer ratchet end of said differential arm, a cam slot at the outer end of said cam arm, a U-shaped member pivoted beneath said cam arm, a pin eccentrically placed on said U-shaped member and traveling in said slot, a finger beneath said U-shaped member pivoted on the same axis, a lug on said finger traveling in the space between said U-shaped arms, a helical spring interposed between 125 130

one of said arms and said lug, a pawl co-operating with said ratchet mounted on a shaft, an arm mounted on said shaft, a finger attached to the outer end of said arm and 5 adapted to contact with a cam at its other end, a cam member intermittently brought into contact with the outer end of said finger, resilient means for returning said differential arm and its coöperating mechanism to 10 its normally inoperative position, whereby when said differential arm and coöperating mechanism are moved by a coin to their operative position they are locked in such position and when said coin has been eliminated they are unlocked and returned to 15 their normal position.

7. In a coin registering mechanism, a hopper comprising an inclined rotatable disk to lift the coins therefrom, differential operating mechanism, a cam arm attached to said differential operating mechanism, a U-shaped member pivoted beneath said cam arm, a coin eliminating finger attached thereto, resilient means between the arms 20 of said U-shaped member, one end of which abuts against one arm and the other end of which rests against an abutment on the coin eliminating finger pivoted on the same axis as said U-shaped member, 25 a pin on said U-shaped member traveling in a slot in the cam arm, said slot being substantially on a straight line at its extremities and semicircular in its medium portion, resilient means to hold said differential and 30 coin eliminating mechanism in inoperative position normally, means to lock said mechanism in position for eliminating a coin, and means to unlock said mechanism, whereby 35 when said pin on said U-shaped member travels through the straight portion of said slot the U-shaped member will not be operated, but will become operative when said pin engages the semicircular portion of said slot resulting in the elimination of a coin. 40

45 8. In a coin eliminating mechanism, a cam arm, means to operate said cam arm, a slot therein substantially on a straight line at either end and semicircular at its medium portion, a U-shaped member pivoted beneath 50 said cam arm, a pin thereon traveling in said slot, a resilient finger pivoted on the same axis as said U-shaped member, an abutment on said finger lying between the arms of said U-shaped member, and a helical spring be- 55 tween one of said arms and said abutment.

9. In a coin eliminating mechanism, a cam arm, means to operate said cam arm, a slot therein substantially on a straight line at either end and semicircular on its medium 60 portion, a U-shaped member pivoted beneath said cam arm, a pin thereon traveling in said

slot, a resilient finger pivoted on the same axis as said U-shaped member, an abutment on said finger lying between the arms of said U-shaped member, said finger being substantially flat at its outer end, the remainder of said finger being substantially flat but at a different angle from the outer end, and a helical spring between one of said arms and said abutment. 65

10. In a coin registering mechanism, a hopper comprising an inclined rotatable disk to lift coins therefrom, a differential operating mechanism, a cam arm, a slot therein, a U-shaped member pivoted thereunder, a pin on said U-shaped member traveling in said slot, a finger pivoted on the same axis as said U-shaped member, an abutment on said pin, a helical spring between one of said U-shaped members and said abutment, resilient means to retain said differential operating mechanism and accompanying mechanism in its inoperative position normally, a ratchet on one end of said differential operating mechanism, a pawl co-operating with said ratchet, means to release said pawl from said ratchet to unlock said mechanism, a star wheel, means connected with said differential mechanism to lift said star wheel according to the denomination 80 of a coin operating said differential mechanism to engage teeth of a proper series on a rack to rotate said star wheel and register the denomination of the coin on a register, whereby, when a coin of predetermined denomination operates said differential mechanism it will operate said differential mechanism and said coin eliminating mechanism, interposing said finger in the path of said coin and diverting it to a receptacle while 90 a coin of another denomination will register its value but not operate said coin eliminating mechanism, passing to another receptacle. 95

11. In a coin registering mechanism, a hopper comprising an inclined rotatable disk to lift coins therefrom, a differential operating mechanism, a cam, a slot therein, a U-shaped member pivoted on the frame, a pin on said U-shaped member traveling in said 105 slot, a finger pivoted on said frame, a lug on said finger, a helical spring between one of said U-shaped arms and said lug, a locked compartment for eliminated coins, another compartment for coins not eliminated, 110 whereby coins of predetermined denomination are eliminated and placed in another receptacle and coins of another denomination are not eliminated. 115

In testimony whereof I affix my signature.

FLOYD A. BURKITT.
